ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD-CUTTING MECHANISM FOR LOOMS

Application filed October 12, 1926. Serial No. 141,194.

This invention relates to thread cutting mechanism for a weft replenishing loom of the pick-and-pick type, in which a plurality of shuttle boxes are provided at the magazine end of the loom.

When a substantially exhausted weft carrier is replaced, it is necessary to cut and remove the trailing weft end attached to the ejected weft carrier. At the same time it is necessary to leave intact the weft ends extending to the inactive shuttles at the magazine end of the loom.

It is the general object of my present invention to provide a thread cutting mechanism of an improved type and so constructed that it will co-operate with and sever the thread extending to the ejected weft carrier, but will not sever the threads extending to the inactive shuttles.

Another object is to provide a thread cutter which will sever the ejected weft end adjacent the open end of the shuttle box and that will hold the portion of weft extending to the selvage in position for engagement by a second thread cutter located adjacent the selvage.

My invention further relates to arrangements and combinations of parts which will be hereinafter described and more particularly pointed out in the appended claims.

A preferred form of the invention is shown in the drawings in which

Fig. 1 is a plan view of the magazine end of a loom embodying my improvements;

Fig. 2 is a front elevation of the lay and rotary shuttle boxes, taken along the line 2-2 in Fig. 1;

Fig. 3 is an enlarged left hand sectional elevation, taken substantially along the line 3-3 in Fig. 1;

Fig. 4 is a left hand sectional elevation, taken along the line 4-4 in Fig. 1;

Fig. 5 is a plan view of the thread cutter, adjacent the selvage, looking in the direction of the arrow 5 in Fig. 4;

Fig. 6 is a detail sectional rear elevation, taken along the line 6-6 in Fig. 4;

Fig. 7 is an enlarged side elevation of the movable thread cutter shown in Fig. 3; and

Fig. 8 is a sectional front elevation, taken along the line 8-8 in Fig. 7.

Referring to the drawings, I have indicated parts of a pick-and-pick loom of the general type shown and described in my prior application, Serial No. 16,791, filed March 19, 1925.

I have indicated a loom frame 10, a lay 11, and a plurality of rotary shuttle boxes 12, mounted upon a support 13 and moved angularly through the selective co-operation of a gear 14 and rack bars 15. The parts thus far described are fully disclosed in my prior application and in themselves form no separate part of my present invention, which relates particularly to the thread cutting mechanism which I will now describe.

For the purpose of disposing of the weft end left trailing from the ejected weft carrier, I have provided two thread cutting devices, one of which is located adjacent the selvage of the fabric, and the other of which is movably mounted adjacent the open ends of the shuttle boxes. The thread cutter adjacent the selvage operates in a substantially fixed position, while the thread cutter adjacent the shuttle boxes is movable rearward to operative position.

I will first describe the movable thread cutter which severs the thread adjacent the shuttle boxes. This thread cutter comprises two cutting jaws 20 and 21 (Fig. 3), the jaw 20 projecting rearward from a supporting member 22 mounted on a fixed pivot 23. The movable jaw 21 is pivoted at 24 on the member 22 and a spring 25 acts to open the jaws whenever the movable jaw is released, as will be hereinafter described.

The movable jaw is provided with an upwardly extending arm 26 having a cam lug 27. A hook arm 28 is pivoted at 29 on the breast-beam 30 and is normally positioned to engage the lug 27 and thus hold the movable thread cutter in forward or inoperative position, with the jaws closed as indicated in Fig. 3.

The hook arm 28 is forwardly extended, as indicated at 32, and is provided with a cam face 33 engaged by a stud 34 at the upper end of an arm 35 secured to the rod or shaft 36

by which an indication of weft exhaustion is transmitted from the weft detecting mechanism to the magazine. Whenever a transfer is indicated, the shaft 36 moves in the direction of the arrow *a* in Fig. 3, and the stud 34 acts against the cam surface 33 to depress the hook arm 28 and release the movable thread cutter, which thereupon moves rearward to operative position under the influence of a relatively strong spring 38 (Fig. 3). The rearward position of the thread cutter is determined by an adjustable stop screw 39, engaging a lug 40 on the loom frame 10.

A spring plate 41 (Figs. 7 and 8) is secured to the side of the movable jaw 21 and acts to hold the jaws in assembled relation and also to yieldingly engage the fixed jaw 20 when the cutter is closed and thus retain the severed weft end in position for engagement by the second thread cutter, to be described.

Upon indication of transfer, the movable thread cutter is released as above described, and moves to the position indicated in dotted lines in Fig. 3, with the parts of the thread cutter disposed as indicated in Fig. 7. As the lay 11 then moves forward, a stud 44 mounted on a bracket 45 carried by the lay engages the upwardly extending arm 26 of the thread cutter and first closes the cutting jaws and thereafter moves the thread cutter forward to position for re-engagement by the hook arm 28. The movable thread cutter is thus released for a single operation only upon indication of transfer.

As the thread cutter moves forward, it raises the severed weft end *W* (Fig. 2) and holds it in a position substantially separated from the ends *W'* extending to the shuttles in the shuttle boxes. In this position the ejected weft end *W* may be engaged by a hook-shaped knife 50 (Fig. 4) formed on a slide 51 mounted in a guide-way or casing 52 on the rear end of a yieldingly mounted bar 53. A spring 54 holds the knife 50 yieldingly in rearward position, and a depending lug 55 extends downward from the knife 50 into the path of the lay 11. The position of the knife 50 in relation to the severed weft end *W* and to the other weft ends *W'* is clearly indicated in Figs. 1 and 2 and is of great importance, as the problem of severing the ejected weft end without at the same time severing the other weft ends in a pick-and-pick loom has been the cause of a great deal of difficulty. The usual temple more closely adjacent the selvage will commonly be used in addition to the two thread cutters shown in the drawings, but the temple is not illustrated in this application.

Having described the details of construction of my improved thread cutting mechanism, the operation thereof will be readily apparent. The movable thread cutter is released upon every indication of weft exhaustion and moves rearward to promptly

engage the ejected weft end. As the lay moves forward, the ejected weft end is severed and gripped by the movable thread cutter and is carried forward and upward to a position which separates it from the other weft ends. The thread cutter holds it so that it may be engaged by the second thread cutter 50, which in turn is engaged by the lay and is moved forward to cut the ejected weft end adjacent the selvage. The ejected weft end is thus severed at two points, one adjacent the selvage and one adjacent the shuttle box and the severed portion is held by the movable thread cutter until the jaws are opened upon the next rearward movement thereof upon indication of further weft exhaustion.

Having thus described my invention and the advantages thereof, I do not wish to be limited to the details herein disclosed otherwise than as set forth in the claims, but what I claim is:—

1. In a weft replenishing pick-and-pick loom, a lay, a plurality of shuttle boxes movably mounted at each end thereof, means to move the shuttle boxes at the replenishing end of the lay so that the active shuttle box will always be elevated above the inactive shuttle boxes, and means to sever the trailing weft end of the ejected weft carrier immediately after indication of weft exhaustion and at points adjacent the shuttle box and also adjacent the selvage, while leaving the wefts of the inactive shuttles intact.

2. In a weft replenishing pick-and-pick loom, a lay, a plurality of shuttle boxes movably mounted at each end thereof, means to move the shuttle boxes at the replenishing end of the lay so that the active shuttle box will always be elevated above the inactive shuttle boxes, and means to sever and hold the trailing weft end of the ejected weft carrier immediately after indication of weft exhaustion and to thereafter move said severed end forward and continuously upward and to retain said weft end in raised position, while leaving the wefts of the inactive shuttles intact.

3. In a weft replenishing pick-and-pick loom, a lay, a plurality of shuttle boxes movably mounted at each end thereof, means to move the shuttle boxes at the replenishing end of the lay so that the active shuttle box will always be elevated above the inactive shuttle boxes, means to cut the trailing weft end of the ejected weft carrier and to grip and elevate the severed end, and means to thereafter cut said severed end a second time at a point substantially nearer the selvage while the first severed part of said weft end is held elevated and the wefts of the inactive shuttles remain intact.

4. In a weft replenishing pick-and-pick loom, a lay, a plurality of shuttle boxes movably mounted at each end thereof, means to

move the shuttle boxes at the replenishing end of the lay so that the active shuttle box will always be elevated above the inactive shuttle boxes, means to sever and hold the trailing weft end of the ejected weft carrier immediately after indication of weft exhaustion, and to thereafter elevate the weft holding means by a forward and upward movement, and additional means effective to engage and sever the weft end, while thus held, at a point substantially nearer the selvage while leaving the wefts of the inactive shuttles intact.

5. In a weft replenishing pick-and-pick loom, a lay, a plurality of shuttle boxes movably mounted at each end thereof, means to move the shuttle boxes at the replenishing end of the lay so that the active shuttle box will always be elevated above the inactive shuttle boxes, means to cut the trailing weft end of the ejected weft carrier and to grip and elevate the severed end, and to thereafter hold said severed end until a further indication of weft exhaustion, and a hook shaped cutter adjacent the selvage effective to separate the trailing weft end from the weft threads extending to the shuttles in the shuttle boxes and to sever said trailing end a second time, while a part thereof is still held elevated and 20 while the wefts of the inactive shuttles remain intact.

6. In a weft replenishing pick-and-pick loom, a lay, a plurality of shuttle boxes movably mounted at each end thereof, means to move the shuttle boxes at the replenishing end of the lay so that the active shuttle box will always be elevated above the inactive shuttle boxes, means to cut the trailing weft end of the ejected weft carrier and to grip and elevate the severed end, and to thereafter hold said severed end until a further indication of weft exhaustion, and a hook shaped cutter adjacent the selvage effective to separate the trailing weft end from the weft threads extending to the shuttles in the shuttle boxes and to sever said trailing end a second time while the wefts of the inactive shuttles remain intact, both of said cutters being actuated by the lay on its forward movements and said first cutter being operated once only and being thereafter maintained in inoperative forward position until again released upon indication of transfer.

7. In a weft replenishing pick-and-pick loom, a lay, a plurality of shuttle boxes movably mounted at each end thereof, means to move the shuttle boxes at the replenishing end of the lay so that the active shuttle box will always be elevated above the inactive shuttle boxes, a thread cutter operative adjacent the open ends of the shuttle boxes and movable to and from operative position, means to hold said cutter normally in forward inoperative position, means to release said cutter upon indication of weft exhaustion, and means to

thereafter actuate said cutter and return said cutter to normal inoperative position by a continuous upward movement as the lay moves forward, said cutter when in inoperative position being substantially elevated above its weft-engaging operative position.

8. In a weft replenishing pick-and-pick loom, a lay having a plurality of shifting shuttle boxes movably mounted at each end thereof, means adjacent the open end of the active shuttle box effective to cut and hold the trailing weft end of an ejected weft carrier in the active shuttle box on the first forward movement of the lay after indication of weft exhaustion, and means to separate the trailing weft end from the weft threads extending to the inactive shuttles and to thereafter sever said separated weft end a second time and substantially nearer the selvage, while leaving the wefts of the inactive shuttles intact.

In testimony whereof I have hereunto affixed my signature.

ALBERT A. GORDON.
